United States Patent Office

Des. 184,591
Patented Mar. 10, 1959

184,591

AUTOMOBILE BODY

Noble S. Williams, Sturbridge, Mass., assignor to American Optical Company, Southbridge, Mass., a voluntary association of Massachusetts

Application October 8, 1957, Serial No. 48,012

Term of patent 14 years

(Cl. D14—3)

Fig. 1

Fig. 2

Fig. 3

Fig. 1 is a perspective view of an automobile body embodying my new design; and

Fig. 2 is a side elevational view of the automobile body of Fig. 1.

Fig. 3 is a rear view of the part of the automobile body shown by the full lines in Figs. 1 and 2.

The dominant features of my new design are shown in full lines in the drawing.

I claim:

The ornamental design for an automobile body, substantially as shown and described.
